UNITED STATES PATENT OFFICE.

WILLIAM J. LAUSTERER, OF JAMESTOWN, NEW YORK, ASSIGNOR, BY MESNE ASSIGNMENTS, TO EMPIRE VOTING MACHINE COMPANY, A CORPORATION OF NEW YORK.

INTERLOCKING MECHANISM FOR VOTING-MACHINES.

1,084,092.

Specification of Letters Patent.

Patented Jan. 13, 1914.

Application filed March 22, 1910. Serial No. 551,021.

To all whom it may concern:

Be it known that I, WILLIAM J. LAUSTERER, a citizen of the United States, residing at Jamestown, in the county of Chautauqua and State of New York, have invented certain new and useful Improvements in Interlocking Mechanisms for Voting-Machines, of which the following is a specification.

10 This invention relates to the interlocking mechanism for voting machines, in which a number of voting keys or ballot indicators are provided for several candidates, which candidates and their keys are grouped according to the requirements of the ballot and of the election, so that a predetermined number of keys can be voted in each of the groups so formed and no more.

15 The interlocking mechanism is shown as applied to a machine of the type illustrated in Patent 938126 Dean Oct. 26, 1909, and application 238388, Dean.

20 This interlocking mechanism is an improvement on interlocking mechanisms known as the parallel channel type, as distinguished from the single channel type, of which latter type Patents 853822, 857800, and 793666 embody illustrations.

25 The machines illustrated in the foregoing patents all have their keys arranged in parallel office lines and in party lines extend transverse to these office lines. The interlocking mechanisms of these machines are separated from each other by office lines 30 so that in one way or another the dividing line between consecutive office lines may be maintained or eliminated as the requirements of the election may make it necessary to permit the voter to vote for one, two, three or even more candidates in a group. In electing 35 supervisors in San Francisco it is necessary to permit each voter to vote for eighteen out of all the candidates nominated by all the parties and in electing judges in some

40 localities it is necessary to permit the voter to select from all of the candidates nominated a large number. So too with Representatives and presidential electors in some cases. The interlocking mechanism is 45 intended to prevent the voter from voting for more candidates than he is by law entitled to vote for. The interlocking mechanism must be capable of limiting the voter to this extent with certainty so as to make 50 it unnecessary for the election officers to in-

spect his ballot and see that he has not violated the election law in voting for more candidates than he is entitled to vote for. The interlocking mechanism must also permit the voter to vote the last key in the group as easily as it permits him to vote the first key of the group, or substantially so, so that the interlock will not interfere with or defeat the efforts of a timid or a weak voter in his efforts to vote, and it should be that light and easy in its operation as not to interfere with the voting of a straight ticket or the simultaneous operation of a large number of keys. These three features of the interlock may be referred to first, the strength of the interlock, which prevents overvoting, second, the flexibility of the interlock, or that quality of permitting the last key to be voted as easily as the first, and third, the lightness of its operation, which permits the easy operation simultaneously of a large number of keys controlled by the interlock. In interlocks heretofore devised these three desirable features could be secured in combination only in comparatively small groups, some interlocks in this respect being of course better than others. The interlock of my invention will secure these three desirable results in combination in a group even larger than will any of the interlocking devices heretofore referred to.

55 This is the object of my invention, to increase the strength, flexibility and lightness of operation of the interlocking mechanism and the means by which these results are secured will presently be explained.

60 It will be understood of course that the invention is capable of application to meet interlocking requirements that exist elsewhere than in voting machines, and to interlock the movement of other moving parts than voting keys.

65 In the accompanying drawings, Figure 1 illustrates a top plan view of the machine, partly broken away so as to omit several of the office lines. Fig. 2 is a side elevation of the machine, the casing being partly broken away, so as to show a portion of the interlocking mechanism. Fig. 3 is a section on the line 3^x, 3^x of Fig. 2. Fig. 4 is a detail in perspective of an interlocking wedge attached to a key, the interlocking blocks co-operating therewith, and the grouping wedge of an office line. Fig. 5 is a detail of

an interlocking roller, such as is used in a grouping channel. Fig. 6 is a detail of the interlocking wedge attached to the individual key for voting for candidates. Fig. 5 7 is a detail of an interlocking channel 14 showing that the interlocking blocks are fastened at one end of the channel and are free to move in the other direction only. Fig. 8 10 is a detail showing the connection between the interlocking strap 18 and its wedge 19.

Like reference numerals refer to like parts in the accompanying drawings and specification.

In Figs. 1 and 2, reference numeral 1 refers to the voting keys which are arranged on the keyboard 2 of the voting machine in parallel lines. One of these keys is provided for each candidate to be voted on. The lines of keys extending horizontally in Fig. 1 are office lines and the lines and keys extending vertically in Fig. 1 may be properly referred to for convenience as party lines. Fig. 1 is shown partly broken away so that several office lines and keys are wholly omitted and the party lines of keys are to that extent shortened. It will be understood of course that the party lines of keys may be extended indefinitely in the construction of the machine, the machine being built correspondingly large so as to accommodate the maximum ticket which may be voted on it in any election. The keys 1, 1 shown in Fig. 2 represent the last office line on the machine. Each of these keys has 25 a stem 3 extending down into the machine. This stem engages with a rocker arm 4 pivoted on a shaft 5. The key is voted by being depressed and in depressing the key the short end of the rocker arm 4 which engages 30 with the key is carried down and the long end of the rocker arm is carried up. These details of my interlocking mechanism are old and are shown here merely for the sake of convenience, it being understood that 35 other forms of voting devices may be used in their stead.

Connected to the long arm of the rocker arm 4 is the interlocking strap and wedge 6, which wedge is more fully shown in Figs. 4 and 6. This wedge is in fact a combination of several wedges and in shape somewhat resembles a fork having three prongs or tines, the object of the several wedges being in short not only to spread the interlocking blocks with which the middle wedge comes into contact, but to pull them together again by means of the two outside wedges. To secure this result I provide the central wedge 7 having the two beveled surfaces 50 thereon connecting the parallel sides of the thin and the thick parts of the wedge. The outer prongs 8 and 9 are provided with wedges which are just the reverse in their operation to the wedge 7, so that as the 55 wedge 7 is raised to spread the blocks, the

wedges 8 and 9 permit the spreading of the blocks and when the wedge 7 is moved in the opposite direction the wedges 8 and 9 operate on the blocks to draw them together. Interlocking blocks 10 are used in connection with these wedges, such as is shown in Fig. 4. The intermediate blocks have a recess 11 cut in each end of each block, while in the end blocks 12 of each office line such recesses are unnecessary at the outer end. Each of these intermediate blocks also has slots 13 cut therein. When two interlocking blocks are placed end to end in the interlocking channel the recesses 11, 11 of the abutting blocks form a slot which embraces the wedge 7. The blocks will ordinarily remain in abutment when the wedge 7 is in the position shown in Fig. 4, and will be spread apart when the wedge is raised by the voting or depressing of the key. The wedges 8 and 9 engage with the slots 13 and cause the interlocking blocks 10 to be drawn together again when the key is unvoted or brought back to normal position.

It will of course be understood that one of the end blocks is normally held stationary so that it cannot move in either direction longitudinally, and that all of the intermediate blocks and the other end block such as shown at 12 are free to move along the channel 14 by which they are supported. It will also be understood that one of these interlocking channels 14 is provided for each of the office lines on the machine, these channels being substantially the same as those illustrated in the Dean patent and applications above referred to. These interlocking channels are all mounted and supported substantially parallel to each other. At the end of each channel 14 as shown in Fig. 2 is supported a bell crank 15, which bell crank has one arm 16 projecting upwardly and maintaining constant engagement with the end block 12 of its particular office line, while the other arm 17 of the bell crank projects sidewise and somewhat below the horizontal and has connected thereto the interlocking strap 18 to the lower end of which is connected the interlocking wedge 19.

It will now be understood that when one key is voted in an office line the end block 12 will be moved to the right from the position shown in Fig. 4 and Fig. 2 and will cause the bell crank lever to rock around its pivot, raising the strap 18. A second wedge 7 voted in the same office line will cause the bell crank to rock still farther and will cause still further the elevation of the strap 18 with its wedge 19. A further operation of keys in the same office line will still further rock the bell crank 15 and still further elevate the strap 18 and its wedge 19. Ordinarily seven keys are provided for candidates in each office line and one key 130

is provided for the blank column. This number however is purely arbitrary, it having been found by experience in elections that it is sufficient. It is seldom that more than seven parties place candidates in nomination or that there are more than seven candidates nominated for one office, except in groups as has been above explained, so that it is not necessary ordinarily to provide for more than seven candidates in each office line whether the office be governor to which but one candidate can be elected, or supervisors or judges to which a number of candidates can be elected. However it will be understood that if necessary my invention may be applied to machines having ten, twelve or even more party lines of keys, it only being necessary in such cases to lengthen the arms of the bell cranks 15 so that the ends of the arms may travel a greater lineal distance without having made a greater angular movement.

The interlocking straps 18 are provided on their ends with the interlocking wedges 19. The ends of the straps 18 and their wedges 19 are all embraced by a grouping channel 20 in which grouping channel is carried interlocking rollers 21, this channel and its interlocking rollers being substantially the same as the channel and the pin rollers illustrated in my prior Patent 793666, each of the rollers being provided with a pin hole 22 through which the grouping pin 23 may pass to fasten it in its appropriate place in the interlocking channel and with an annular recess 24 which is wide and deep enough so that the recess formed by two of said rollers when in contact will loosely embrace the interlocking strap 18. The interlocking strap is narrowed as shown at 25 in Fig. 4, so that the length of the recess 24 in the interlocking rollers 21 and the width of the wedge 19 may be diminished accordingly and to also provide shoulders 26 on the bottom of the interlocking strap 18, whereby it can the more positively engage the interlocking wedge 19.

Each of the interlocking wedges 19 is made broader than its interlocking strap 18 at 25, and it is on the portion of the wedge 19 that lies on either side of the strap at 25 on which the interlocking contact or pressure occurs. The interlocking strap is not placed under pressure at all and the whole interlocking pressure is between the rollers 21 or between the rollers 21 and the wedges that separate them.

The interlocking wedge 19 is channeled as shown to receive the interlocking strap positively therein.

As shown in Fig. 3, the interlocking straps 18 normally lie parallel to each other and extend from the bell cranks 15 down to the interlocking wedges 19. These interlocking

straps are spaced apart by the rollers 21. These rollers are normally held opposite the pin holes 26 in the interlocking channel 20 by the grouping pins 23, which grouping pins pass through the interlocking channel and serve to hold the rollers in place. As the rollers are held in this position space is left between them to permit the insertion therebetween of the first step of the wedge 19. It will be understood from an inspection of Figs. 3 and 4 that the wedge 18 is provided with a series of steps which are herein referred to for convenience by the characters 19^a, 19^b, 19^c, 19^d, 19^e, 19^f, 19^g and 19^h. The wedge in this way is formed of eight pairs of sides, all of which sides are parallel to each other and are connected by short bevels, which bevels or cams have substantially the thickness equal to one-half of the distance between consecutive rollers when such rollers are held in position by the grouping pins.

It will be understood that as the wedges 19 are raised, the two adjacent bevels connecting the two consecutive sets of parallel sides operate on the adjacent rollers to either take up the space normally existing between such rollers or, as in the case of a group, to move the rollers apart or farther apart a distance equal to that to which the rollers normally are held apart by the grouping pins. On these wedges 19 is provided a pair of parallel sides for each key in the office line of keys, the thickness of the wedge from top to bottom increasing at a uniform rate as above described. That is, the increased thickness of the wedge between one pair of parallel sides over the preceding pair of parallel sides is equal to the space normally between two of the interlocking rollers when held in position by the grouping pin, it being understood of course that proper allowance is made in these measurements to minimize friction without substantially interfering with the accuracy of the fitting of the parts, it being also understood that the holes 22 through the interlocking rollers may be somewhat larger than the grouping pins which pass through them, so as to permit lateral adjustment of the rollers on their grouping pins and thus maintain parallel alinement between the rollers even if the grouping pins do not have parallel alinement, due to error in the placing of holes for the grouping pins in the interlocking channel.

It will also be understood that instead of the bell crank 15 I may attach a chain or a cord to the end block 12, which cord will extend back toward the first interlocking wedge 7 and pass down over a pulley conveniently mounted under the block 12. To the end of this cord or chain may be attached the interlocking strap 18, so that by this construction as well the interlocking

strap 18 will be lifted in response to the voting of keys in its particular office channel. Other changes will suggest themselves as well.

5 It will now be understood that as successive keys are voted in an office line, the end block 12 will travel out to the right as shown in Fig. 4, and will lift the interlocking strap 18 through successive steps making 10 the wedge 19 engage with its successive steps with the adjacent interlocking rollers 21 spreading them farther and farther apart. In this way in a large group one or more of 15 these wedges 19 may be raised to its full height, separating the adjacent interlocking rollers to correspond. For example, in a group of twenty-one, three of these wedges may each be raised seven steps and they should then take up all the space between 20 the grouping pins which mark the ends of the groups so that no other wedge could be raised a single step or a whole step. It is apparent that if an additional key is pressed down so as to raise the interlocking wedge 25 19 a partial step it will not be effective for any objectionable purpose (that is, beating the machine or overvoting the interlock) because the key will not have advanced far enough to cause the operation of its counter 30 and as soon as the voter ceases to press down on the key the parts will practically resume their normal condition.

It will further be understood that the counter operating mechanism is not positioned or operated by the key until after the key has moved far enough to complete its interlock, consequently the incomplete movement to which the extra key is limited by the interlock will not and can not be 40 made to cause the overvoting of the key.

It will be seen by my construction that errors of displacement of the interlocking blocks are confined to the office line in which they originate and are not communicated as 45 errors to the grouping wedges 19 and their interlocking rollers. It has always been recognized that as the wedges 7 swing side-wise and swing away from a line perpendicular with their interlocking blocks, that 50 their displacement increases proportionately to the secant of the angle which they make with such perpendicular line, and that some extra space must be allowed between the interlocking blocks in each office line to compensate for this error, and it is also apparent that if this excess space of several office 55 lines could be combined, it would amount to enough to permit the voting of an extra key. If the length of the office line is increased by increasing the number of keys and interlocking wedges embodied therein, this error will rapidly increase unless the length of the interlocking strap 6 is correspondingly increased. This error is also 60 increased by increasing the displacement of

the interlocking wedge 7. This error will not ordinarily interfere with the accuracy of single candidate groups so as to permit the voting of two keys in one office line, even if the party rows on the machine are increased to fifteen or even more, but as soon as several office lines are thrown together an extra key can be voted in the group provided the excess space in all the interlocking channels of the several office lines can be added together. If the spear heads 19 had but two sides tapering to an edge instead of a series of parallel sides, the errors of the successive office lines could be added together so as to permit the over-voting of a group, but by dividing the sides of the wedges 19 into successive steps corresponding to their movement, due to the successive voting of keys, and by making the interval between successive pairs of sides as short and as abrupt as possible I prevent this accumulation of errors.

It is also understood that if the wedges 19 have but a single pair of tapered sides an extra key might be voted by springing the interlocking channel. That is, in the group one key might be voted and thereafter a straight ticket key might be voted carrying with it all the keys of another party line. The combined effect of this would be to cause all of the wedges 19 to press upward against the interlocking channel, raising the channel a trifling amount, which amount would be practically multiplied by the number of office lines on the group and added to any other errors that might exist in the interlock, which combination of errors would possibly be sufficient to permit the voting of the extra key. In this case the wedges 19 would not displace the rollers laterally any more than the normal amount, the error being due principally to the elevation of all the rollers. This error cannot be perpetrated, so to speak, on my interlock without forcing up the channel 20 by an amount equal to the distance between the centers of successive pairs of steps on the wedges 19, and the ordinary mountings of the interlocking channel will prevent this to a certainty. Long before this could happen either the strap 6 or 18 would break, and these straps can ordinarily be made with a breaking strength of many hundreds of pounds, so that with any ordinarily useful machine my interlocking mechanism can be depended upon to prevent the voter from making mistakes or from making a wilful misuse of the machine.

Having thus described my invention, what I claim as new and patentable is as follows:

1. The combination in a voting machine of keys arranged in parallel office lines, of wedges connected to and operated by each of said keys, interlocking blocks separated or drawn together by said wedges, a channel

for supporting said interlocking blocks, said channel preventing said blocks from spreading except in one direction, a bell crank pivoted at the free end of each channel and engaged 5 with the end block in the channel, and being rocked thereby, a progressively stepped wedge connected to said bell crank and being operated thereby, said stepped wedges being embraced by a grouping channel, spacing devices carried in said grouping channel and separating said stepped wedges.

2. The combination in a voting machine of a channel, a series of interlocking blocks supported in said channel, a three-pronged wedge for engaging with and operating said blocks, the middle prong passing between said blocks, the outer prongs passing through perforations in said blocks.

3. The combination in a voting machine 20 of a channel, a series of interlocking blocks supported in said channel, a three-pronged wedge for engaging with and operating said blocks, the middle prong passing between said blocks, the outer prongs passing through 25 perforations in said blocks, said wedge operating to separate said blocks when moved in one direction and to draw said blocks together when moved in the reverse direction.

4. The combination in a voting machine 30 of an interlocking mechanism therefor comprising interlocking blocks, a three-pronged wedge for engaging with and operating said blocks, cams on each of said prongs, cams on the outer prongs being shaped reversely 35 to the cams on the middle prong.

5. The combination in a voting machine of an interlocking mechanism therefor comprising a channel, a series of interlocking blocks carried in said channel, wedges for 40 separating said blocks, a bell crank pivoted below the end of said channel, one arm of said crank engaging with the end block and the other end of said crank having a wedge suspended therefrom.

45 6. The combination in a voting machine

of an interlocking mechanism therefor comprising a channel, a series of interlocking blocks carried in said channel, wedges for separating said blocks, a bell crank pivoted below the end of said channel, one arm of 50 said crank engaging with the end block and the other end of said crank having a wedge suspended therefrom, said wedge having stepped sides and being progressively movable.

55

7. In an interlocking mechanism the combination of cylindrical rollers having annular recesses central thereof, an interlocking channel supporting said rollers, an interlocking wedge having stepped parallel 60 sides, an interlocking strap connected centrally to the edge of said wedge, passing through the annular recesses of said rollers and holding said wedge substantially perpendicular to said channel.

65

8. The combination of a pair of interlocking rollers placed side by side in abutment, each of said rollers being cylindrical in shape and having an annular recess central thereof, an interlocking strap passing between 70 said rollers, said strap having a stepped interlocking wedge connected thereto, said wedge being progressively movable, to first separate said rollers and then move them apart by successive steps.

75

9. The combination in the interlocking mechanism for a voting machine of a wedge having a series of stepped sides thereon, a recess cut from the edge to the base of the wedge centrally of one of the tapered sides 80 of said wedge, an interlocking strap engaging in said recess of said wedge and having an enlarged end positively engaging with the base of said wedge.

In testimony whereof I affix my signature 85 in presence of two witnesses.

WILLIAM J. LAUSTERER.
